Benjamin H. Pearson of Warner New Hampshire

Letters Patent.

The schedule referred to in these Letters Patent and making part of the same containing a description in the words of the said Benjamin H. Pearson himself of his improvement in the Cooking Stove.

To all whom it may concern,

Be it known that I Benjamin H. Pearson of Warner in the County of Merrimack and State of New Hampshire, have invented an improvement in the stove intended principally for cooking which I denominate the open frame cooking stove, and that the following is a full and exact description thereof,

Fig 1. represents the top part, the distance from D to E, is 16 inches - from A to C, 16 inches, from F to G 27 inches, being the part over the fire place.

The distance from C to B, is 26 inches from O to P 20 inches - from P to R 17 inches, & from R to E, 6 inches being the part over the back part of the stove, and the oven, K C is a damper which may be turned either to R or S, to any the fire under A, 5 and 6. - Numbers 1. 2. 3. 4. 5. 6. are circles of different sizes to be used for kitchen furniture. The distance from A to C is 32 inches from G to I, 6 inches from H to I, 38 inches, this represents the height M N and L to L are dampers to turn the fire under the oven, as will be seen in Fig 1 D, which represents the side view of the stove, - a. b. c. e. represents the part over the fire, the distance from a to b, 20 inches, from b to c, 10 inches, from a to c, 12 inches, from c to b 3 inches from f to g 17 inches the height of the back part of the stove i. j. k. h. represent the oven situated in the back part of the stove, the distance from c to h, is 11 inches and it is 18 inches square on the top and the bottom with the exception of the fire corners being a little clefted. The distance from a to e is 16 inches, being the back part of the fire place, the oven is situated one inch higher than the back part of the fire place and from c to m is one inch and a half, and the front part of the oven extends one inch above to K.

The distance from J to m is 2 and a half inches. The distance from the bottom of the stove to the bottom of the oven is 3 inches, and the same distance at

11.

at the top of the oven to the top of the stove and the same space at the end.

The top of the oven extends the whole width of the stove, the bottom and the side opposite the door leaves a space of 2 inches for the fire to pass so that the fire passes all over the oven except on the side of the door, Fig. 1. This represents the front part of the stove. The distance from A to B is 18 inches - from C to D 6 inches from E to F represents a crank on which are placed two half cast wheels for the purpose of raising the grate in the fire place formed at B with a cog wheel A. F in Fig 1. represents the flue, all the parts connected with the fire place, the top and sides, are to be of cast iron. the outside of the stove with the oven is to be of sheet iron, this stove may be altered in its form and in its particular arrangement of its parts, whilst those features which constitute the difference between it and other stoves for cooking and heating apartments are still retained, It is therefore alone which I claim as my invention, and for which I ask a patent. They consist in heating the oven on fire parts - its particular situation to give a draft under the oven with an open fire place.

The damper K. C to turn the fire under Nos. 5 & 6 and the turning of a crank with the two half cast wheels to raise or lower the grate in the fire place, whether the same be effected in the exact way which I have indicated or in any other operating upon the same principle and producing similar results.

Witness,

Daniel Patten,

J. C. Badger

Benjamin H. Pease
